UNITED STATES PATENT OFFICE.

SIGURD WALFRID ALBERT WIKNER, OF NEWCASTLE-UPON-TYNE, ENGLAND, AS-SIGNOR OF ONE-EIGHTH TO NEWCASTLE-UPON-TYNE & GATESHEAD GAS COMPANY, OF NEWCASTLE-UPON-TYNE, ENGLAND.

MEANS FOR DEHYDRATING LIQUIDS SUCH AS COAL TAR, CRUDE PETROLEUM, AND THE LIKE.

Application filed May 12, 1922. Serial No. 560,372.

To all whom it may concern:

Be it known that I, SIGURD WALFRID ALBERT WIKNER, a subject of the King of Great Britain, residing at 33 Grainger Street west, Newcastle-upon-Tyne, England, have invented a new and useful Improved Means for Dehydrating Liquids Such as Coal Tar, Crude Petroleum, and the like, of which the following is a specification.

10 This invention relates to means for dehydrating liquids, such as coal tar, crude petroleum and the like.

According to this invention a heating vessel is provided with means for keeping liquid therein at a substantially constant level and with a heating coil just below this level, through which coil heating fluid can be circulated, and a pipe or pipes are arranged in the vessel by which the water vapour expelled from the liquid, and it may be other vapour or vapours, can pass down through the bulk of the liquid whereby the liquid is heated and the vapour is condensed.

The invention is illustrated by the accompanying drawing, in which Figure 1 is a longitudinal section, Figure 2 a transverse section and Figure 3 a plan.

The pipe A delivers an excess of the liquid to be treated from a reservoir into a chamber I provided with an overflow J from which any surplus liquid delivered passes back to the reservoir. This chamber communicates through a pipe K with the bottom of a closed tank B the level of the liquid 25 in which is therefore kept constant at the

level of the overflow J. Just below the level of the liquid is a series of pipes L to which steam can be introduced through a pipe M and from which it passes away through a pipe N. The water vapour and any other vapour, which are driven off from the liquid by the heat in the pipes L, pass down through pipes O to coils P in which the vapours are condensed so that no heat is lost, and the condensed vapours flow away from these coils P which may be connected if desired to a small condenser. The dehydrated liquid is removed from the tank B through a pipe Q.

What I claim is:

In means for dehydrating liquids, the combination of a closed tank, means for supplying liquid to the bottom thereof, means for maintaining the level of the liquid in the tank substantially constant, a heating coil disposed just below that level and extending from one side to the other of the tank, and a plurality of pipes leading from the interior of the tank and having openings disposed above the level of the surface of the liquid in the tank, each pipe extending in coil formation from end to end of the tank and finally communicating with the exterior of the tank adjacent the bottom thereof.

In testimony that I claim the foregoing as my invention I have signed my name this 26th day of April, 1922.

SIGURD WALFRID ALBERT WIKNER
